(57) **CLAIM**

The ornamental design for a bag rack, as shown and described.

DESCRIPTION

FIG. 1 is a perspective view of a bag rack showing a new design;

FIG. 2 is a left side elevation view thereof, the right side being a mirror image;

FIG. 3 is a rear elevation view thereof;

FIG. 4 is a front elevation view thereof;

FIG. 5 is a top plan view thereof;

FIG. 6 is a bottom plan view thereof;

FIG. 7 is front perspective view thereof, showing the bag rack with a plurality of bags thereon and showing a bag in an open configuration;

FIG. 8 is a perspective view of the bag rack showing an alternate embodiment;

FIG. 9 is a left side elevation view thereof, the right side being a mirror image;

FIG. 10 is a rear elevation view thereof;

FIG. 11 is a front elevation view thereof;

FIG. 12 is a top plan view thereof;

FIG. 13 is a bottom plan view thereof; and,

FIG. 14 is front perspective view thereof, showing the bag rack with a plurality of bags thereon and showing a bag in an open configuration.

The dashed lines shown in the drawings are for environmental purposes only and form no part of the claimed design.

1 Claim, 14 Drawing Sheets

Related U.S. Application Data

division of application No. 29/717,361, filed on Dec. 17, 2019, now Pat. No. Des. 993,657.
